W. SCHROER

RAKE

Filed Oct. 18, 1924

W. Schroer,
Inventor

By *Barbara A. Brixen*
Attorney

UNITED STATES PATENT OFFICE.

WILLIAM SCHROER, OF MILWAUKEE, WISCONSIN.

RAKE.

Application filed October 18, 1924. Serial No. 744,412.

To all whom it may concern:

Be it known that I, WILLIAM SCHROER, a citizen of the United States, residing at Milwaukee, in the county of Milwaukee and 5 State of Wisconsin, have invented certain new and useful Improvements in Rakes, of which the following is a specification.

This invention relates broadly to an improved rake, and it has specific reference to 10 several improved structural features. The first feature is the peculiar construction of the head, wherein the same is well adapted to accommodate the teeth, the same being formed with a groove, in which the heads 15 on the upper ends of the teeth are received, a rod being placed in the groove and retained in place, to at all times maintain the point of the teeth in a plane with each other.

Another feature is the specific construction 20 of certain of the teeth, wherein they are provided on their lower ends with means for facilitating the dragging of the rake over rough surfaces.

A third, but no less important feature, is 25 the construction of the handle, and the means for attaching it to the head when the handle is permitted to be folded alongside of the head, to render the rake easily compact for shipping, etc.

30 Other features and advantages of the invention will become apparent from the following description and the drawing.

In the accompanying drawing, forming a 35 part of this application, and in which like numerals are employed to designate like parts throughout the same:

Figure 1 is a top plan view of a rake, constructed in accordance with the present invention.

40 Figure 2 is a detail view of the central portion of the rake, showing the construction of the handle and its connecting means.

Figure 3 is an enlarged sectional view, 45 taken on the plane of the line 3-3 of Figure 1.

Figure 4 is a similar view, taken on the line 4-4 of Figure 1.

Figure 5 is a detail perspective view of one 50 of the rake teeth.

Referring to the drawings in detail, where- 55 in the reference character 1 designates the cylindrical head, in the present instance the said head is provided along its top and from end to end with a longitudinal groove. Ex-

tending downwardly from this groove and 55 to the bottom side of the head, are vertical longitudinally spaced bores through which the rod like teeth 2 extend. As seen more clearly in Figure 5, the tooth is provided, at its top with a polygonal elongated head 3, 60 which is seated in the aforesaid groove, to prevent rotation of the teeth. Fitted into the groove is a longitudinal retaining rod 4, which is held in place by appropriate clamps 5. At each end, and in the middle, I provide 65 special rack teeth of the construction shown in Figure 4. Referring to this figure, it will be seen that the tooth is provided with screw threads, at its lower end, and a spherical ball or knob 6 is screwed thereon. Ob- 70 viously these balls constitute shoes, which serve to permit the rake to ride easily, upon irregular surfaces.

Observing now, the foldable handle, it is 75 to be seen that the same is designated by 75 the reference character 7. It is provided, on its inner end, with a ferrule 8 and a flat ex- 80 tension plate 9 is bolted, or otherwise secured thereto, the plate extending considerably be- 85 yond the free end of the ferrule and being provided at one edge with a notch 10, and at its free end with an opening for passage 90 of a pivot pin 11. For the purpose of connecting this handle with the rake head, I provide a special two part clamp 12, com- 85 prising a pair of plates 13 of duplicate formation. Each plate is provided with a channel, and when the channel shaped por- 95 tions are brought together, they form a clamp for connection of the plate with the head 1. In the arrangement shown, four bolts 14 are utilized for maintaining the plates in place. A spacer and tie 15 is con- 100 nected with the inner pair of bolts, for re- taining the plates in spaced relation. The plates are formed with aligned arcuate slots 16 and the extension 9 carries a bolt 17, which extends through the slot. The bolt, in turn, is provided with a thumb nut, and it is obvious that with this arrangement the handle may be moved to any desired angle 105 with respect to the head, and retained in that position. Also, it may be folded alongside of the head, and retained in that position to render the rake compact for shipping, storage, etc. When it is swung to the last named position, the aforesaid notch 10 co- 110 operates with the spacer 15, at one of the

bolts 14, to permit the handle to lie in close spaced relation with respect to the rake head.

I claim:

5 A rake comprising a head provided with a longitudinal slot, and a plurality of longitudinally spaced vertical bores extending downwardly from said slot, teeth extending through said bores, said teeth having heads

on their upper ends fitted into said slots to 10 prevent the rotation thereof, a retaining rod seated in said slot and engaging said head to maintain the teeth in horizontal alignment, and clamps for securing said rod in place.

15 In testimony whereof I affix my signature.

WILLIAM SCHROER.
